ATTORNEY

J. J. L. Wright

WITNESS:

UNITED STATES PATENT OFFICE.

FRANK V. BOOKER, OF CHEYENNE, WYOMING.

SELF-CLOSING BOX.

Application filed February 15, 1924. Serial No. 693,108.

To all whom it may concern:

Be it known that I, FRANK V. BOOKER, a citizen of the United States, residing at Cheyenne, in the county of Laramie and 5 State of Wyoming, have invented new and useful Improvements in Self-Closing Boxes, of which the following is a specification.

This invention relates to novelty receptacles and has for its object the provision of 10 a unique, artistic and attractive box which may be of any desired size and shape as well as materials and formed of a suitable or preferred number of sections, the essential feature being that the device is normally held 15 closed by the inherent resilience of the material employed, and the arrangement being of such a nature that opening is readily effected by the application of pressure to the ends.

20 Another object is the provision of a box of this character which is particularly useful for containing or holding trinkets, matches, tobacco or other articles.

Yet another object is the provision of a 25 device of this character which lends itself readily to use as an advertising device as its simplicity and cheapness will permit manufacture and disposition on a wholesale scale if such is desired.

30 With the above and other objects and advantages in view the invention consists in the details of construction to be hereinafter more fully described and claimed and illustrated in the accompanying drawings, in 35 which:

Figure 1 is a side elevation of the device in closed position,

Figure 2 is an end elevation thereof,

Figure 3 is a top plan view,

40 Figure 4 is a side elevation showing the device held within the hand and squeezed to effect opening,

Figure 5 is an end elevation showing the device in opened up position,

45 Figure 6 is a top plan view thereof showing it open.

Referring more particularly to the drawings I have, in the present instance, shown the box as comprised by three similar sections of some suitable resilient material, such for instance, as sole leather, celluloid,

spring metal or the like. The material as well as the size and shape may be varied within wide limits. One section 10 is here represented as constituting the bottom, to 55 the edges of which are secured the edges of the side sections 11 and 12. All the edges of all three sections are curved so that the natural tendency of the bottom section 10 to flex into planar condition causes the side 60 sections to be disposed normally against each other with their free edges abutting and defining a closure.

The device is well adapted for use as a tobacco pouch, coin purse or holder of trinkets or other articles and it is obvious that it may be made as ornamental as desired depending upon the use to which it is to be put and the expense to be involved in the manufacture. To effect opening, it is 70 merely necessary to apply pressure to the ends 13 whereupon the resultant bowing of the bottom and sides will cause the top to gape open, permitting access to the interior.

While I have shown and described the 75 preferred embodiment of my invention it is of course to be understood that I reserve the right to make such changes in the form, construction and arrangement of parts as will not depart from the spirit of the invention 80 or the scope of the subjoined claims.

Having thus described my invention I 85 claim:

1. A device of the character described comprising a plurality of sections having 85 curved edges, one section constituting the bottom and the other sections being secured thereto at the edges thereof, the tendency of the bowed bottom to straighten into planar condition acting to hold the other 90 sections closed.

2. A device of the character described comprising a bottom section and a pair of similar side sections secured thereto at the edges thereof, the other edges of the side 95 sections being free to define an opening, the bottom being curved whereby its natural tendency to straighten will hold the side sections with the free edges thereof together.

In testimony whereof I affix my signature.

FRANK V. BOOKER.
